UNITED STATES PATENT OFFICE.

GEORGE A. FLACCUS, OF WHEELING, WEST VIRGINIA.

DESIGN FOR A SHIPPING VESSEL.

SPECIFICATION forming part of Design No. 29,438, dated October 4, 1898.

Application filed September 1, 1898. Serial No. 690,231. Term of patent 7 years.

To all whom it may concern:

Be it known that I, GEORGE A. FLACCUS, a citizen of the United States, residing at Wheeling, in the county of Ohio and State of 5 West Virginia, have invented and produced a new and original Design for Shipping Vessels; and I do hereby declare the following to be a full, clear, and exact description of the same, reference being had to the accompanying drawings, forming a part thereof.

In the accompanying drawings, Figure 1 is a perspective view of a shipping vessel embodying my design, and Fig. 2 is a vertical longitudinal section through the same.

15 The leading feature of my design consists of a shipping vessel made approximately in the form of a battle-ship or gunboat and having a removable cover, the cover portion representing the upper portion of the ship and 20 the lower portion representing the hull of the ship.

In the accompanying drawings, A represents the body of the vessel, which is made to represent approximately the outline of the 25 hull of a ship and is provided with a closed

bottom *a* and is open at top, and also on its inner surface near its upper edge with an inwardly-extending ledge *a'*.

The cover B is made of a shape to represent approximately the upper portion of a battleship or gunboat and has two decks *b b'*, smoke-stacks *b² b³*, ventilators *b⁴ b⁵ b⁶*, a military mast *b⁷*, protruding guns *b⁸ b⁹*, and other configurations to make it represent a battleship or gunboat. The cover is also formed 35 with an outwardly and downwardly extending flange C, which when the cover is in position on the body of the vessel rests on the ledge *a'* thereof.

Having now described my invention, what I claim as new, and desire to secure by Letters Patent, is—

The design for a shipping vessel, substantially as herein shown and described.

In testimony whereof I hereunto affix my signature in presence of two witnesses.

GEORGE A. FLACCUS.

Witnesses:

J. M. MALTZ,

Wm. C. FLACCUS.
